UNITED STATES PATENT OFFICE.

ROBERT KERSHAW, OF PHILADELPHIA, PENNSYLVANIA.

IMPROVEMENT IN MODES OF PRODUCING VARIEGATED THREADS.

Specification forming part of Letters Patent No. **58,836**, dated October 16, 1866.

To all whom it may concern:

Be it known that I, ROBERT KERSHAW, of Philadelphia, Pennsylvania, have invented a Mode or Process of Producing Variegated Threads; and I do hereby declare the following to be a full, clear, and exact description of the same, reference being had to the accompanying drawings, and to the letters of reference marked thereon.

My invention relates to the production of variegated threads to be used in the manufacture of variegated textile fabrics; and my invention consists in producing a variegated thread by imparting to a central thread, or to a guide which conveys a wrapping-thread to the central thread, such a varying, irregular, intermittent, or reversing traversing motion as will cause the wrapping-thread to be wound on the central thread in different quantities at different points.

In order to enable others skilled in the art to practice my invention, I will now proceed to describe certain mechanism by which it may be carried into effect.

On reference to the accompanying drawings which form a part of this specification, Figure 1 is a side elevation of a machine for carrying out my mode of producing variegated threads; Fig. 2, a sectional elevation; Fig. 3, a plan view; Fig. 4, a detached view of part of the machine, and Fig. 5 a sectional view of Fig. 4.

Similar letters refer to similar parts throughout the several views.

A is the base of the machine, to which are secured the side frames, B and B', and between the latter extend shelves or platforms C and D. In the side frames turn shafts F, G, H, and to the former is secured a roller, E, on which bears a detachable presser-roller, E', the journals of the latter projecting into slots a in the side frames. On one end of the shaft F is a pinion, b, the teeth of which are adapted to those of a sectional pinion, c, secured to the driving-shaft G, and on the outer end of the latter is a grooved pulley, d. On the shaft H are two grooved pulleys, e and f, and round the latter and round the pulley d extends a band, g.

In suitable bearings in the base-plate A and in the platform C turns a vertical spindle, I,

round a grooved pulley, h, on which and round the pulley e passes a band, g'.

In the platform C is secured a ring, K, on which slides the usual traveler i, and on the upper end of the shaft or spindle I, which projects through the ring K, is a detachable spool, L.

To the platform D, directly above the spindle I, is secured a plate, M, in the outer end of which is an opening n, and to the upper side of the plate is fastened the lower end of an inclined split tube, N, in which are slots s s'.

To the platform D is secured a rod, O, for a purpose described hereinafter.

The devices above described, with the exception of the tube N and the sectional pinion c, are similar to those used in an ordinary twisting-machine.

The thread or cord x to be spun or twisted is conducted from between the feed-rollers E E', through the tube N, opening n, and traveler i, to the spool L.

As the spool L revolves, the traveler i will be carried rapidly round on the ring K, and the thread or cord x will be twisted or spun in a manner too well known to those familiar with this class of machines to need particular description.

A spool, Y, containing a thread, y, of any suitable color, is placed on the rod O, and the thread from the spool is passed through the slot s in the tube N and secured to the cord x. As the cord is spun or twisted the thread y is lapped round it, a knot, u, being thus formed on the cord at a point opposite the slot s.

When the teeth of the sectional pinion c are brought into contact with those of the pinion b the roller E will be caused to turn a portion of a revolution; and the cord x will be passed quickly downward through the tube N for a short distance, and will then again be held stationary until the teeth of the pinion c are again brought into contact with those of the pinion b.

As the cord x passes quickly through the tube N the thread y will be lapped spirally round the cord instead of being formed into a knot. A second knot, however, will be formed as before the instant the cord x is again stationary. As the cord x is twisted and fed intermittently to the spool L, as described, the

thread y is lapped on the same in alternate knots and spirals, and a variegated thread of the character shown in Fig. 4 is thus produced.

The distance between the knots is regulated by the amount of traverse imparted to the cord x by the action of the rollers, while the size of the knots is determined by the thickness of the thread y , the rapidity of the spinning or twisting motion imparted to the cord x , and the length of time the latter is held stationary.

The cord x may consist of two or more strands of different colors. Two different colored threads, y , may also be introduced together through the same slot s , or separately through slots opposite each other in different sides of the tube N .

A thread having the knots alternately of different colors may be produced by introducing a thread, y , of one color through the slot s and another thread of a different color through the slot s' , as shown in Fig. 5.

By using a fine thread, y , and imparting a tight tension to the same, it may be so buried in the cord x as only to appear at points where it is lapped in knots on the same.

Another variety of thread may be formed by drawing back the cord x a short distance after it has been fed forward, or by imparting a reciprocating motion to the guide-tube N . The cord may also be fed continuously forward, but at different degrees of speed, another variety of thread being thus produced.

When it is desired to lap a thread round a

zephyr or other cord, which, when in a finished state, should be loosely twisted, a tight twist is first imparted to the cord. It is then introduced into the machine and untwisted as it passes through the tube N , the thread y being lapped round the cord during the untwisting of the latter.

Although I have illustrated and described peculiar mechanism for carrying out my invention, it will be evident that the machinery may be modified, altered, and other machinery substituted for causing one thread to be lapped round another by imparting a spinning or twisting motion to the central thread, so as to draw the outer thread onto the same.

Without confining myself, therefore, to the specific devices herein described—

I claim as my invention and desire to secure by Letters Patent—

Producing a variegated thread by imparting to a central thread, or to a guide which conveys a lapping thread to the central thread, such a varying, irregular, intermittent, or reversing traversing motion as will cause the lapping thread to be wound on the central thread in different quantities at different points.

In testimony whereof I have signed my name to this specification in the presence of two subscribing witnesses.

ROBERT KERSHAW.
